UNITED STATES PATENT OFFICE.

OLUF TYBERG, OF BROOKLYN, NEW YORK.

MECHANICAL MOVEMENT FOR PRINTING DEVICES.

SPECIFICATION forming part of Letters Patent No. 749,000, dated January 5, 1904.

Application filed May 8, 1897. Serial No. 635,681. (No model.)

To all whom it may concern:

Be it known that I, OLUF TYBERG, a citizen of the United States, residing at Brooklyn, in the county of Kings and State of New York, have invented certain new and useful Improvements in Mechanical Movements for Printing Devices, of which the following is a specification.

This invention is applicable in all cases where it is desired at a given instant to maintain at rest a point upon the surface of a wheel or cylinder, whether for taking impressions, as in type-writing machines, or otherwise, and is applicable to printing - telegraphs as well as to type-writers.

The invention involves a new principle or mode of operation of printing devices embodying a rotating type-wheel or printing-wheel, means for obtaining impressions from the characters thereon, and means for at will selecting the characters or types from which impressions are to be taken.

It consists, generally stated, in an organization, comprising a wheel revolving about its axis and having types fixed upon its face, respectively, in permanent radial relation thereto, combined with rotary wheel-driving devices continuously revolved and having permanent interlocking or intermeshing positive driving connection with the type-wheel and yet so constructed and operating that any printing-point upon the surface of the type-wheel may at will be caused to assume a position at rest, or substantially so, with reference to a printing-plane in which succeeding impressions are to be taken. This is accomplished in the embodiment of the invention herein specifically described by a compound motion which consists of the rotary motion of the wheel about its axis and a bodily motion of the wheel at right angles to its axis in a direction opposite to the motion of that side of the wheel from which the impression is to be taken and occurring at the moment of impression, the axis of the wheel being stationary at other times.

In the accompanying drawings, Figure 1 is a plan view of the machine. Fig. 2 is a side view, and Fig. 3 a front view; Fig. 4, a diagram showing the mechanical movement involved.

A is a base-plate having two upright projections A' and A², upon which is mounted in centers a' and a² a rocking frame B. This rocking frame B has two arms b' and b², projecting toward the rear of the machine and which form the bearings for the type-wheel shaft c, and another downward-projecting arm b³. To the one end of the type-wheel shaft c is fastened a gear c², which engages with a pinion b³, fastened to pulley b⁴. This pulley b⁴ is mounted freely on the hub of the rocking frame B and may be driven by a belt by some convenient power, motor or treadle, and when so driven will keep the type-wheel shaft c continually revolving. To the type-wheel shaft c and between the arms b' and b² is fastened a drum c³, having a series of projections or pins c⁴ arranged spirally on the circumference. Beneath said drum c³ are arranged a series of key-levers D, pivoted on a common rod D', which is fixed in lugs A³, which are supported by or form part of projections A' and A². The levers D are arranged so that each one is directly in line with a corresponding pin c⁴ of the drum c³. The key-levers D are provided with keys and in their normal positions are held up against the cross-piece a³ (fastened to the front of projections A' and A²) by springs d', mounted on angle-piece a⁴, which is also fastened to the front of projections A' and A² and which also acts as a limit-stop for the motion of the key-levers D. On the other end of the type-wheel shaft c is mounted the type-wheel E, which is revolved by the type-wheel shaft c by means of a key c⁵, while it is free to move longitudinally back and forth on the shaft c. The type-wheel E has two rows of letters or types fixed thereon, each type in permanent radial relation to the axis of the wheel and the type in each row corresponding in number to the number of pins c⁴ on the drum c³. The number of rows, as well as the number of letters on each row of the type-wheel, may be varied to suit requirements. The type-wheel E has a flanged hub e', into which is fitted an arm F, pivoted on a shaft F', mounted in bearing A⁴, which is a part of projection A'. To the other end of shaft F' is fastened a key-lever G. To the lower end of arm F is attached a spring F², which tends

through the arm F to keep the type-wheel E normally against the flange c^6 on the end of the type-wheel shaft c.

Directly in line with the inner row of the 5 type-wheel E is mounted a hammer H, pivoted to shaft h' and mounted in bearing A^5 , which forms part of the base-frame A. To the other end of the shaft h' is fixed an arm H' , which through the rod h^2 is connected to the arm 10 b^{13} , which forms part of the rocking frame B. A spring h^8 , attached to arm H' , keeps the hammer H, as well as the rocking frame B, in a normal position, all resting against the pin g, mounted in projection A'.

15 The operation of the machine is as follows: The type-wheel shaft c, carrying the type-wheel E and drum c^8 , is continually revolved in the manner already described. On the depression of one of the key-levers D the rear 20 projection or arm d^3 will move into the path of its corresponding pin c^4 of the drum c^8 . When the pin strikes the arm d^3 , the power transmitted through the type-wheel shaft to revolve the type-wheel and drum will at once 25 begin to lift the type-wheel shaft, and in so doing will enable the pin c^4 to slide off the arm d^3 .

Referring now to the diagram, the projection on the drum is indicated by c^4 and the 30 outline of the type-wheel in its normal position by E, with its center in c, while $a' a^2$ indicate the center of the rocking frame in which the type-wheel is mounted. When the projection or pin on the drum strikes the 35 key-lever arm d^3 , the type-wheel shaft c is moved into the position $c^{\times}$, thus allowing the pin c^4 to slide off the arm d^3 from n to $n^{\times}$. It will now be seen that as the distances from the point p on the circumference of the type- 40 wheel E to the points n and $n^{\times}$ on the arm d^3 are equal, as well as the distances of p to c and $c^{\times}$, the point p will remain stationary during the engagement of the pin c^4 with the arm d^3 .

45 By the movement of the rocking-frame center from c to $c^{\times}$ an impulse is given to the hammer H through its connection with this rocking frame and which will make it strike the point p of the type-wheel E while it remains at rest relative to the printing-plane.

Through control of the key-lever G either row of letters on the type-wheel may be brought into line with the hammer H.

It is apparent from the comprehensive 55 character of this invention that I do not limit myself to the organization shown, since it is obvious that the principle of operation herein set forth may be embodied in a large variety of mechanical forms.

60 When a wheel continuously rotated by a rotating driver has a bodily movement imparted to it at right angles to its axis, a point on one side of the wheel will remain substantially at rest or have a rolling or pivotal 65 movement with reference to a given point at its periphery, the behavior being similar to

that of a wheel rolling upon a surface when each point upon the periphery remains momentarily relatively at rest with reference to corresponding points on the surface upon which it rolls.

I claim as my invention—

1. A wheel continuously revolving on a normally stationary but movable axis and means for momentarily causing any point on the 75 surface of said wheel to assume a position of rest at a predetermined point.

2. A wheel continuously revolving on its axis combined with means for at will moving the wheel bodily at right angles to its axis, 80 the resultant of such two motions of the wheel maintaining momentarily at rest in a predetermined position any point on the surface of the wheel.

3. The combination of a rotating wheel, a 85 continuously-revolving driver-wheel, an interlocking connection between the two wheels by which the first-named wheel is positively rotated by the latter and means whereby one of said wheels may at will be moved bodily 90 at right angles to its axis to thereby momentarily maintain at rest a point on the surface of the latter wheel.

4. A type-wheel continuously revolving on its axis and having type fixed upon its face 95 in permanent radial relation, respectively, to its axis, means for momentarily causing any type on the surface of said wheel to assume a position at rest, relative to a particular stationary printing-plane.

5. A type-wheel continuously revolving on its axis and having type fixed upon its face in permanent radial relation, respectively, to its axis, means for momentarily causing any type on the surface of said wheel to assume 105 a position at rest with relation to a stationary printing-plane, means for taking an impression from a type on the surface of said wheel while such point is momentarily at rest in the printing-plane, and means whereby the 110 operator may, at will, select the type from which impressions are to be taken.

6. A type-wheel continuously revolving on a normally stationary but movable axis, means for momentarily causing any printing-point on the surface of the said wheel to assume a position at rest relative to a particular stationary printing-plane, means for taking an impression from a printing-point on the surface of said wheel while such point is 120 momentarily at rest in the printing-plane, and means whereby the operator may, at will, select the points upon the surface of the wheel from which impressions are to be taken.

7. A type-wheel, continuously revolving on 125 its axis, means for momentarily causing any printing-point on the surface of said wheel to assume a position at rest with relation to a stationary printing-plane by moving the wheel bodily at right angles to its axis at the instant 130 a point of the wheel is to be at rest, and means for taking an impression from a printing-

- point on the surface of said wheel while such point is momentarily at rest in the printing-plane.
8. A type-wheel, continuously revolving on its axis, means for momentarily causing any printing-point on the surface of said wheel to assume a position at rest with relation to a stationary printing-plane by moving the wheel bodily at right angles to its axis at the instant a point of the wheel is to be at rest, means for taking an impression from a printing-point on the surface of said wheel while such point is momentarily at rest in the printing-plane, and means whereby the operator may, at will, select the points upon the surface of the wheel from which impressions are to be taken.
9. A type-wheel continuously revolving on a normally stationary but movable axis, means for intermittently moving the wheel bodily at right angles to its axis, the resultant of such two movements maintaining momentarily at rest any printing-point on the surface of said wheel relative to a stationary printing-plane, and means for taking an impression from any desired printing-point on the surface of said wheel at said printing-point while it is momentarily at rest in said stationary printing-plane.
10. A type-wheel continuously revolving on its axis, means for moving it bodily at right angles to its axis, means whereby the power of revolving the wheel may be applied to the mechanism for bodily moving the wheel, and whereby any printing-point on the surface of said wheel may be momentarily maintained at rest relative to a stationary printing-plane.
11. A type-wheel continuously revolving on a normally stationary but movable axis, means for moving it endwise in line with its axis and means for momentarily causing any printing-point on the surface of said wheel to assume a position at rest relative to a particular stationary printing-plane.
12. A type-wheel continuously revolving on a normally stationary but movable axis, means for moving it endwise in line with its axis, means for momentarily causing any printing-point on the surface of said wheel to assume a position at rest relative to a particular stationary printing-plane, and means for taking an impression from the surface of said wheel at said printing-point while it is momentarily at rest in said printing-plane.
13. A type-wheel continuously revolving on its axis, means for moving it endwise in line with its axis, means for momentarily causing any printing-point on the surface of said wheel to assume a position at rest with relation to a stationary printing-plane by moving the wheel bodily at right angles to its axis at the instant a point on the wheel is to be at rest.
14. A type-wheel continuously revolving on its axis, means for momentarily causing any printing-point on the surface of said wheel to assume a position at rest relative to a particu-

lar stationary printing-plane, a hammer, and means for causing said hammer to take an impression from said wheel at said stationary printing-plane while said printing-point is momentarily at rest in said printing-plane.

15. A type-wheel, continuously revolving on its axis, means for causing any printing-point on the surface of said wheel to assume a position at rest relative to a stationary printing-plane by moving the wheel bodily at right angles to its axis at the instant a point on the wheel is to be maintained at rest, a hammer, and means for causing said hammer to take an impression from said point of the wheel while at rest in the printing-plane.

16. A type-wheel continuously revolving on its axis and having type fixed upon its face in permanent radial relation, respectively, to its axis, a series of finger-keys, means for momentarily causing any type on the surface of said wheel to assume a position at rest, relative to a particular printing-plane by the depression of the corresponding finger-key.

17. A type-wheel continuously revolving on its axis, a series of finger-keys, means for momentarily causing any type on the surface of said wheel to assume a position at rest relative to a particular printing-plane by the depression of a corresponding key, a hammer, and means for causing said hammer to take an impression from said type while at rest in the printing-plane.

18. The combination of a rotating type-wheel, a continuously-revolving driver-wheel, an interlocking connection between the two wheels by which the type-wheel is positively rotated and means whereby one of said wheels may at will be moved bodily at right angles to its axis to thereby maintain at rest a given type on the type-wheel during the moment of printing.

19. The combination of a rotating type-wheel having type fixed on its face in permanent radial relation, respectively, to its axis, a continuously-revolving driver-wheel, an interlocking connection between the two wheels by which the type-wheel is positively rotated and means whereby one of said wheels may at will be moved bodily at right angles to its axis to thereby maintain at rest a given type on the type-wheel during the moment of printing.

20. The combination of a rotating wheel, a continuously-revolving driver-wheel, an interlocking connection between the two wheels by which the type-wheel is positively rotated, means whereby one of said wheels may at will be moved bodily at right angles to its axis to thereby maintain at rest a given type on the type-wheel during the moment of printing and means whereby the operator may at will select any one of the type from which an impression is to be taken.

21. The combination of a rotating type-wheel having type fixed on its face in permanent radial relation respectively to its axis, a continuously-revolving driver-wheel, an in-

- terlocking connection between the two wheels by which the type-wheel is positively rotated, means whereby one of said wheels may at will be moved bodily at right angles to its axis 5 to thereby maintain at rest a given type on the type-wheel during the moment of printing and means whereby the operator may at will select any one of the type from which an impression is to be taken.
- 10 22. The combination of a rotating type-wheel having two or more rows of type upon its periphery, a continuously-revolving driver-wheel, an interlocking connection by which the type-wheel is positively rotated by the 15 driver-wheel, means for moving the type-wheel axially to bring either series of type upon its circumference into the printing-plane and means whereby one of said wheels may at will be moved bodily at right angles to its axis to thereby maintain at rest a given 20 character on the type-wheel during the moment of printing.

23. The combination of a rotating type-wheel having two or more rows of type upon its periphery, a continuously-revolving driver-wheel, an interlocking connection by which the type-wheel is positively rotated by the driver-wheel, means for moving the type-wheel axially to bring either series of type upon its circumference into the printing-plane and means whereby one of said wheels may at will be moved bodily at right angles to its axis to thereby maintain at rest a given character on the type-wheel during the moment of printing and means whereby the operator may at will select any one of the type in either series from which an impression is to be taken. 30

In testimony whereof I have hereunto subscribed my name.
